CLAIM

The ornamental design for a container with astrological ornamentation molds, as shown and described.

DESCRIPTION

FIG. 1 is a perspective view of a container with astrological ornamentation molds showing my new design;

FIG. 2 is a top plan thereof;

FIG. 3 is an end view of FIG. 2 as seen from the top side thereof;

FIG. 4 is an end view of FIG. 2 as seen from the bottom side thereof;

FIG. 5 is an end view of FIG. 2 as seen from the left side thereof;

FIG. 6 is an end view of FIG. 2 as seen from the right side thereof;

FIG. 7 is a bottom plan view thereof; and,

FIG. 8 is a cross section view thereof, taken along line 8—8 in FIG. 7.
